UNITED STATES PATENT OFFICE.

EDWARD ALEXANDER MASTERMAN, OF STIRLING, SCOTLAND.

MOORING DEVICE FOR LIGHTER-THAN-AIR AIRCRAFT.

1,373,343.

Specification of Letters Patent. Patented Mar. 29, 1921.

Application filed April 24, 1919. Serial No. 292,465.

To all whom it may concern:

Be it known that I, EDWARD ALEXANDER MASTERMAN, a subject of the King of Great Britain, residing in Stirling, Scotland, have 5 invented certain new and useful Improvements Relating to Mooring Devices for Lighter-Than-Air Aircraft, of which the following is a specification.

The invention relates to mooring devices 10 for lighter-than-air aircraft designed to enable such aircraft to be moored in the open without wind screens or other protection against the effect of wind.

The object of this invention is to moor 15 such craft in such a manner as to prevent both forward and sidewise movement of the ship when moored, and with this object in view the improved mooring device comprises a two-point attachment of mooring ropes 20 both to the mooring mast and to the airship, the points of attachment on the mast being separated from each other laterally as well as the points of attachment of the mooring ropes on the nose of the envelop. This system 25 of attachment prevents the forward surging of the ship which is liable to occur upon cessation of wind gusts and consequent recovery, both of the mast and the airship's envelop, from the strain caused by such gusts. It also prevents the ship "sailing" 30 into the mast, which it is liable to do when moored to a single point on the mast and its head gets slightly off the wind. Furthermore, any tendency of the ship to roll is 35 checked.

The invention comprises, broadly, a mast which is of sufficient height to permit the airship being moored thereto, either just resting on or clear of the ground, and which 40 is bifurcated at its upper end for the attachment of mooring ropes thereto at widely separated points, these ropes being also attached to the envelop at two points separated laterally from each other which do 45 not come into contact with any part of the mooring mast. Means carried by the mast are provided for taking up the slack of the ropes in the operation of mooring the ship.

The invention will be described in sufficient detail to enable it to be clearly understood with reference to the accompanying drawings, wherein Figure 1 is a view on a small scale of the nose of an airship moored to a bifurcated mast in accordance with this 55 invention; Fig. 2 is an elevation on a larger scale of one construction of mooring mast,

showing also the relation thereto when moored of the members on the airship for the attachment of the mooring ropes; Fig. 2^a is an elevation view of the lower end of 60 the mast; Fig. 3 is a cross section of the crutch of the mast; Fig. 4 is an elevation on a still larger scale of one of the winches carried by the mast for hauling in the mooring ropes; Fig. 5 is an elevation partly in section 65 of a footstep bearing for the base of the mast; Fig. 6 is an elevation partly in section of the upper part of a modified construction of mooring mast; and Fig. 7 is an elevation partly in section of the base of an alternative 70 construction of mooring mast which can be tilted so as to vary its effective height. Like reference characters designate corresponding parts in the several figures.

Referring first mainly to Figs. 1 to 5, a 75 vertical mast A terminates at its upper end in a bifurcation or crutch B which may be of any approved design, e. g. the crescent-shaped lattice beam of triangular section shown in Figs. 2 and 3, and which carries at 80 its upper ends or horns the winches C', C².

The triangular section girder shown in Fig. 3 is formed of angle bars b', b², b³ at the three corners braced by tie bars b⁴. Mooring ropes D pass around the barrels c of 85 these winches which, as shown, are rotatable by hand power through worm gear c', and are adapted to be fastened, as by means of spring hooks at their free ends, to eyebolts or the like provided at the steel rings H', H² 90 to which a number of flexible connections 1 are brought from rings J', J² of fabric of the type known as "Parseval rings" attached to the envelop at either side of the nose of the ship. These points of attachment near the nose of the envelop are symmetrically disposed on either side of the vertical longitudinal central plane and the line joining these points preferably intersects the direction of the resultant pressure on the 95 structure due to a head wind. In a rigid or semi-rigid airship the mooring attachments can be applied in any suitable manner to the framing.

A similar fabric ring J³ is attached to the 105 envelop at the underside of the nose in the central vertical plane, and a wire rope K adapted to be fastened to a steel ring H³ connected with the fabric ring J³ passes over pulleys L in the crutch B to a winch C³ at 110 the base of the mast A.

Wire guy ropes F are attached in the

known manner to a steel ring G revoluble on steel rollers arranged at the top of the mast immediately below the crutch, so that mast and crutch are free to rotate about a vertical axis but are restrained by the guy ropes in their motion in any other direction. Alternatively, as shown in the modified construction of Fig. 6, the mast A may be stationary and the crutch B alone rotatable in bearings G' , G^2 provided at the upper end of the mast for a stem B' projecting downwardly from the crutch.

The mast A , particularly if rotatable, is preferably supported at its base on a footstep bearing E of the ball and socket type which allows the mast to rotate freely about a vertical axis and also to take up any inclination to the vertical which it may tend to assume consequent on varying tensions in the guys. Such a footstep bearing is shown in the construction of Fig. 5, wherein in an upper cap M secured to the foot of the mast forms, with an under cap m screwed into the upper cap and secured by studs thereto, a socket for a ball N the stem of which is screwed into a plate O bolted to a foundation plate P which is secured in any usual manner in the ground.

The height of the mast may be varied to suit the requirements of any size of ship it is desired to moor and may be arranged so that the ship is held at such a height that the cars just rest on the ground when the longitudinal axis of the ship is horizontal, or alternatively and preferably at such a height that a considerable inclination is permitted before any part of the ship will come into contact with the ground.

In the operation of mooring, the ship is landed on the aerodrome and walked toward the mast until it is sufficiently near for the wire K to be attached to the mooring ring H^3 , the nose of the envelop is then brought into the crutch B by means of the lower winch C^3 so as to enable men stationed at the upper winches C' , C^2 to attach the ropes D to the rings H' , H^2 respectively.

In rough weather, to facilitate the entrance of the ship into the jaws of the crutch by the handling party, the mast may be swung about its footstep bearing or the crutch may be hinged upon the upper end of the mast so as to permit the arms of the crutch to be lowered.

In the alternative design shown in Fig. 7 the guy ropes are dispensed with and the mast A constructed as a balanced cantalilover pivoted near its lower end on a circular framework or turntable Q and having at its lower end a segment rack or racks A' engaging with a pinion or pinions R operated through suitable gearing such as the worm gears S , S' and connecting shafting by means of a hand wheel S^2 . The supporting framework Q is preferably as shown in the

form of a circular turntable sunk in a pit in the ground and supported on a circular rail T by rollers T' , the upper part of the frame being steadied by rollers T^2 running in a horizontal circular channel guide way U around the top of the pit and by rollers T^3 running on the under surface of the guide way U .

Having thus described the nature of the said invention and the best means I know of carrying the same into practical effect, I claim:

1. Mooring device for aircraft lighter than air, comprising in combination an upwardly extending mast, mooring ropes attached thereto at points separated laterally from each other and members on the aircraft separated laterally from each other for the attachment of the mooring ropes.

2. Mooring device for aircraft lighter than air, comprising an upwardly extending mast, mooring ropes leading therefrom at points separated laterally from each other and means for taking up the slack of said mooring ropes.

3. Mooring device according to claim 1, comprising a bifurcated mast, ropes leading from the limbs of the fork for attachment of the aircraft and means carried by the mast for taking up the slack of the ropes, substantially as described.

4. Mooring device according to claim 1, comprising a crutch carried by an upwardly extending mast, ropes leading from the laterally spread extremities of the crutch for attachment to points on the aircraft abaft the nose laterally separated from each other, winches carried by the crutch for paying out and hauling in the ropes, a rope leading from the center of the crutch for attachment to a point on the aircraft abaft and below the nose, and a winch at the foot of the mast for paying out and hauling in said rope, substantially as described.

5. Mooring device according to claim 1, in which the mooring ropes lead from the ends of a crutch formed as a semi-circular girder.

6. Mooring device according to claim 1, wherein the mast is supported by guys and has a crutch from which the mooring ropes lead and which is rotatable with respect to the said guys.

7. Mooring device according to claim 1, wherein the mast is surmounted by a crutch and supported by guys attached to a ring with respect to which mast and crutch are rotatable.

8. Mooring device according to claim 1, wherein the mast is rotatably supported upon a footstep bearing by guys attached to a ring encircling the mast, substantially as described.

In testimony whereof I have signed my name to this specification.

EDWARD ALEXANDER MASTERMAN.
